UNITED STATES PATENT OFFICE.

HENRY BRUCE VANHOOK, OF WASHINGTON, NORTH CAROLINA.

ATTACHMENT FOR PIANO-PEDALS.

985,304.

Specification of Letters Patent. Patented Feb. 28, 1911.

Application filed June 14, 1910. Serial No. 566,795.

To all whom it may concern:

Be it known that I, HENRY BRUCE VANHOOK, a citizen of the United States of America, and resident of Washington, in the county of Beaufort and State of North Carolina, have invented certain new and useful Improvements in Attachments for Piano-Pedals, of which the following is a specification.

10 This invention relates to musical instruments and particularly to attachments for piano pedals and a piano case designed to coact for the purpose of guarding the openings for the pedals in order to prevent access 15 to the interior of the case of mice or the like or under certain conditions to utilize an attachment for the pedals alone for the purpose of guarding the pedal openings.

An object of this invention is to produce 20 guards for the pedal openings which may be adjusted with relation to the front of the case for the purpose of properly positioning the guards on the pedals in such relation to the front of the case as to effectually guard 25 the openings, as stated.

With the foregoing and other objects in view, the invention consists in the details of construction and in the arrangement and combination of parts to be hereinafter more 30 fully set forth and claimed.

In describing the invention in detail, reference will be had to the accompanying drawings forming part of this specification, wherein like characters denote corresponding 35 parts in the several views, in which—

Figure 1 illustrates a view in elevation of a fragment of a piano case with the invention applied thereto; Fig. 2 illustrates a sectional view showing the case and the guard 40 applied to the case and to the pedal; Fig. 3 illustrates a sectional view of a fragment of a pedal with a guard plate applied thereto; Fig. 4 illustrates a perspective view of a plate and housing designed to coact with 45 the pedal and case; and Fig. 5 illustrates a top plan view of a fragment of the pedal showing the adjustable connection of the guard and pedal.

In these drawings 10, denotes a fragment 50 of a piano case having openings 11 and 12 therein, the latter of which is surrounded on three sides by a plate 13, having on its inner edge an outwardly extending flange 14 forming a housing in which a pedal 15 is movable. The plate 13 may be secured to

the case by any appropriate fastenings but I have shown screws 16 for that purpose.

The pedal 15 is provided with a slot 17 extending longitudinally thereof to receive a bolt 18 which bolt projects below the lower 60 surface of the pedal and has mounted on it the end of a guard 19, the said guard being provided with an aperture 20 for the reception of the bolt 18. As shown in Figs. 2 and 3, the guard extends downwardly and 65 inwardly or rearwardly toward the case which relation of the guard and the case will result in increasing its efficiency owing to the fact that the pedal moves to the position shown in dotted lines in Fig. 2 but rests in the position shown in full lines in Fig. 2. By having the guard extending toward the case the opening in the case is more effectually guarded. By the relation of the 70 guard to the pedal here shown, the pedal is 75 allowed to oscillate without affecting the operative relation of the guard to the opening or to the housing with which it coacts and is adapted to guard an opening in the piano case 10. In Fig. 2, the relation of the 80 guard 19 to the flange 14 is shown and as the said guard is nearly equal in length to the width of the housing formed by the flange 14, the opening in the piano case is 85 closed against the ingress of mice or the like and therefore the interior of the case is guarded against damage.

Under certain conditions, that is to say when the bottom of the case recedes with respect to the front of the case, it may be possible 90 to employ the guard plate 19 without the housing plate and when such conditions are encountered, the guard 19 may move closer toward the front surface of the case through the medium of the adjustable bolt 95 heretofore described. I provide means for guarding the pedal openings of piano cases by a single guard plate for each opening or a guard plate acting in conjunction with a housing plate, thus adapting the invention 100 for piano cases of different constructions.

If desired, I may form the housings or flanges 14 for a plurality of pedal openings on a single plate and as the size of the plate is immaterial, it follows that a plate may be 105 made with one, two or three flanges according to the number of pedals employed on a case.

I claim—

1. An upright piano case having pedal 110

openings therein, a pedal in an opening, a guard plate for said opening, the said plate having an opening therein registering with the pedal opening, and said plate having a flange extending outwardly from the front of the case partially embracing the pedal and guard.

2. An attachment for upright pianos comprising a plate having a pedal opening and a flange at said opening forming a housing, a guard adapted to be secured to a pedal and to coact with the flange, and means for adjustably connecting the guard to a pedal within the housing.

15 3. An upright piano case having a pedal

opening therein, a plate having a pedal opening secured to the case at the pedal opening thereof, and a flange on the plate forming a housing, a pedal having a slot extending longitudinally thereof, a bolt slidable in the slot, a guard mounted on the bolt, said guard being adapted to coact with the housing to form a barrier. 20

In testimony whereof, I affix my signature in the presence of two witnesses.

HENRY BRUCE VANHOOK.
